METALLIC RECEPTACLE AND CLOSURE
THEREFOR

Alvin C. Vick, Toledo, Ohio, assignor, by mesne assignments, to Cornell Securities Corporation, Cleveland, Ohio, a corporation of Delaware

Application December 22, 1930
Serial No. 504,109

4 Claims. (Cl. 220—61)

My invention is an improvement in metallic receptacles and closures therefor and relates more particularly to means for effecting a fluid tight seal between the closure and the receptacle.

One of the objects of my invention is to effectively seal a cover on a receptacle by contracting a clamping ring to press the cover and receptacle together and by uniformly distributing the closing pressure exerted by the ring about the periphery of the cover.

Another object of my invention is to apply a lateral or substantially radial pressure against the cover flange while contracting the ring.

A further object of the invention resides in a ring contracting device for drawing the ends of the clamping ring together to effectively seat and seal a cover on a receptacle, wherein means is provided for varying the sealing pressure about the ring subsequent to the initial contraction of the clamping ring.

Another object of my invention is to construct a clamping ring of the type described which is extremely simple of construction, durable and inexpensive to manufacture.

Other objects and advantages of my invention will become more apparent from the following description of an embodiment thereof reference being made to the accompanying drawing in which like reference characters are employed to designate like parts throughout the same.

In the drawing:—

Figure 1 is a top plan view of an embodiment of my invention.

Figure 2 is a fragmentary enlarged section through a portion of the receptacle, cover and locking ring taken on line 2—2 of Figure 1 and illustrates how the cover is seated on the receptacle to provide a liquid tight seal.

Figure 3 is an enlarged part plan view similar to that of Figure 1 and illustrates the ring on the receptacle in contracted position.

Figure 4 is a view similar to that shown in Figure 3 except that the ring is illustrated in its normal uncontracted position.

Figure 5 is a sectional view taken on line 5—5 of Figure 1, with the cover and receptacle removed.

The embodiment of my invention herein illustrated and described is particularly adapted for use in connection with metallic receptacles such as drums, barrels or the like, for shipping and storing oils or other liquids. Such containers or receptacles are subject to rough handling and are usually made of relatively heavy gauge sheet

metal. It is therefore important that an effective seal between the cover and the receptacle be provided.

Referring now more particularly to the drawing which illustrates one embodiment of my invention, the receptacle is indicated generally at 1 and is provided at its open end with an annular bead 2 rolled outwardly. A cover 3 fits within the open end of the receptacle and is formed with an upwardly and outwardly extending annular flange 4 which rests on a packing 5 supported on the bead 2.

The packing 5 may be made of any suitable flexible material and I prefer to use an annulus of rubber tubing as shown. It will be noted that a portion of the flange 4 is curved in cross section to conform substantially to the curvature of the bead 2, the outer edge of the flange extending just short of a point opposite the greatest diameter of the bead.

I have provided means for seating the cover on the receptacle and pressing the flange of the cover and the bead together on the packing to insure a tight fluid proof seal therebetween. This means includes a contractible channeled clamping ring 6 which is substantially U-shaped in cross section, and in which the upper and lower walls are approximately parallel only for a short distance from their annular edges. Thus, it will be seen that when the ring is assembled on the receptacle as illustrated in Figure 4, and contracted as in Figures 1 and 3 a substantially vertical pressure is exerted by the inclined walls of the ring to press the flange and bead together.

Lugs 7 and 8 may be formed either integrally with one of the walls of the U-shaped ring, or separately and welded thereto. The lugs extend inwardly of the ring and may be raised throughout a portion as indicated at 9.

I have also provided means for contracting the split channeled ring 6 which includes a lever 10 pivotally mounted on one of the lugs 7 by means of a pin 11. This means also includes an adjustable connecting rod 12 slidably mounted in bearings 13 and 14 formed in the lug 8 by rolling over a portion of the lug material. The bearings are separated as at 15 to receive between them an adjusting nut 16 which is threaded on the rod 12. The outer end of the rod terminates in a bearing 17 for receiving a headed pin 18. Connecting links 19 and 20 are pivotally connected at one end to the pin 18 and at their opposite ends to the lever 10 by means of a pin 21. It will be observed that the lever lies in a plane between the links 19 and 20 and for the most part

preferably in a plane outside the upper wall of the ring 6. The link 19 also lies in a plane outside the upper wall of the ring by virtue of the bearing 17 and the spacer washer 22.

- 5 As illustrated in Figure 3, a straight line drawn through the axes of the pins 18 and 21 will lie between the axis of the pin 11 and the adjacent ring section. In this way accidental release of the ring contracted on the receptacle may be prevented, since the pin 18 is thus positioned past a dead center with respect to the pin 11.

I have also provided means for exerting a lateral pressure against the cover flange and the ring, which includes an arm or shoe 23 preferably formed as an extension of the lever 10. This arm terminates in a slightly curved face 24 for engagement with the upwardly extending wall of the cover flange 4.

- 20 As the lever is moved toward the position shown in Figure 3 the arm or shoe 23 engages the cover flange 4 and exerts in increased intensity a lateral pressure on the flange wall and ring. The application of lateral pressure in this way more uniformly distributes the clamping pressure on the flange and bead as the ring is contracted.

25 In order to seal the ring against unauthorized removal, a tab 25 may be welded to one of the ring walls as shown in Figure 5. The tab is apertured to register with an aperture in the lever when the lever is in closed position and a wire and seal may be applied in the usual way.

30 It will be noted that additional clamping or substantially axial pressure may be applied to the flange and bead after the ring is contracted, by simply turning the nut 16 to withdraw the connecting rod to the right in Figures 3 or 4. However, such adjustment may also be made while the ring is normally open as in Figure 4.

35 Various changes may be made in the details of construction and arrangement of parts without departing from the spirit of my invention or the scope of the appended claims.

I claim:

- 40 1. A device for removably sealing a head on a metallic receptacle in fluid tight relation including a contractible channeled ring for pressing the head and receptacle together when the ring is contracted, and means for contracting the ring including a lever pivoted to a portion of the ring, links pivotally connecting another portion of the ring with the lever and means for

limiting the degree of contraction of the ring on the receptacle and head, said last named means including a lug carried by the ring and having a rod receiving bearing formed therein, a threaded rod movable in the bearing and connected with the links, and a nut on said rod to adjust the same axially with respect to the bearing.

- 45 2. A device for removably securing a head on a metallic receptacle in fluid tight relation including a split ring having portions for engaging the head and receptacle to press the same together, means for contracting and expanding the ring to secure or release the head on the receptacle, said means including a lever pivoted to a portion of the ring, a link pivotally connecting another portion of the ring with the lever, and means for limiting the degree of contraction and expansion of the ring on the receptacle and head, said last named means including a bearing member carried by a portion of the ring, a rod movable in the bearing and connected with the link, and means associated with the rod to adjust the same within the bearing.

50 3. A device for removably securing a head on a metallic receptacle in fluid tight relation including a split ring having portions for engagement with the head and receptacle to draw the same tightly together, means for contracting and expanding the ring including a lever and a link pivotally connecting said lever with said ring, and means connected with said link and said ring for selecting any one of a plurality of limits of contraction or expansion of said ring.

- 55 4. A device for removably securing a head on a metallic receptacle in fluid tight relation including a split ring having portions for engaging the head and receptacle to press the same together, means for contracting and expanding the ring to secure or release the head on the receptacle, said means including a lever pivoted to a portion of the ring, a link pivotally connecting another portion of the ring with the lever, and means for limiting the degree of contraction and expansion of the ring on the receptacle and head, said last named means including a bearing member carried by a portion of the ring, a member movable in the bearing and connected with the link, and means associated with said movable member to hold the same within the bearing in an adjusted position.
